US00D898191S

(12) **United States Design Patent** (10) Patent No.: **US D898,191 S**
(45) Date of Patent: **** Oct. 6, 2020**

(54) **CAP OF AN INJECTION DEVICE**(71) Applicant: **Sanofi-Aventis Deutschland GMBH**,
Frankfurt am Main (DE)(72) Inventors: **Courtney Nicholas**, East Greenbush,
NY (US); **Scott Barton**, East
Greenbush, NY (US); **Bart Burgess**,
East Greenbush, NY (US); **Alexei**
Goraltchouk, Cambridge, MA (US)(73) Assignee: **Sanofi-Aventis Deutschland GMBH**,
Frankfurt am Main (DE)(**) Term: **15 Years**(21) Appl. No.: **29/645,291**(22) Filed: **Apr. 25, 2018**(30) **Foreign Application Priority Data**

Oct. 25, 2017 (EM) 004420388

(51) LOC (12) Cl. **24-02**

CLAIM

The ornamental design for a cap of an injection device, substantially as shown and described.

DESCRIPTION

FIG. 1 is a perspective view of a cap of an injection device showing our new design;

FIG. 2 is a second perspective view thereof;

FIG. 3 is a front elevation view thereof;

FIG. 4 is a rear elevation view thereof;

FIG. 5 is a side elevation view thereof;

FIG. 6 is a top plan view thereof; and,

FIG. 7 is a bottom plan view thereof.

The broken lines show portions of the design that form no part of the claimed design
